UNITED STATES PATENT OFFICE.

HENRY M. HUME AND FREDERIC T. HUME, OF NEW YORK, N. Y.

TRAMWAY-SWITCH.

SPECIFICATION forming part of Letters Patent No. 596,368, dated December 28, 1897.

Application filed August 6, 1896. Serial No. 601,868. (No model.)

To all whom it may concern:

Be it known that we, HENRY M. HUME and FREDERIC T. HUME, citizens of the United States, residing at New York, in the county of New York and State of New York, have invented certain new and useful Improvements in Tramway-Switches; and we do hereby declare the following to be a full, clear, and exact description of the invention, such as will enable others skilled in the art to which it appertains to make and use the same.

The object of our invention is to provide a switch for railways which can be operated from the car, thus doing away with the necessity of having a man stationed at every curve, intersection, or other point where cars are switched from one track to another.

It is intended to equip those points where tracks intersect or branch and switches are employed with a device such as that shown by the drawings. At a point distant fifty feet, more or less, from the point where the tracks diverge will be a striking-plate, this striking-plate to consist of two pieces or blocks curved on their inner faces or sides and of sufficient thickness that the top of each piece will be fair or level with the top of the rail. These pieces will be placed one at either side of the rail or at one side of each rail where necessary or desirable, these pieces to be connected by a plate or by bars beneath the rail or rails and so arranged that when one part is close to the rail the other will be removed from the rail by a distance about equal to the diameter of a plunger located on a car. (Not shown.)

Connected to the striking-plate, as described above, will be a lever which will extend along the side of the rail to a point opposite the tongue of the switch proper at the intersection of the tracks, to which tongue it will be connected by a rod passing beneath the rail. In the drawings this bar is shown pivoted at a point intermediate between the points of its connection to the striking-plate and the tongue of the switch. One of the plungers hereinbefore mentioned, having been depressed, strikes upon a traveling or guiding plate and, following the side of the rail, works its way between the rail and the curved side

of the striking-block, forcing the latter outward. The lever-bar, being connected to the striking-block, is either forced away from or brought close to the rail according to which plunger has been depressed, thus moving the tongue at the other end and either closing or opening the switch.

The different parts are to be properly enclosed in iron boxes, as shown in some of the views.

In the drawings, Figure 1 is a top plan of the switch, its two positions being shown in dotted and full lines. Fig. 2 is a section through *y y*, Fig. 1. Fig. 3 is a similar view through *z z*, Fig. 1. Fig. 4 is a section through *w w*, Fig. 1. Fig. 5 is a section through a box to be located at *v v*, Fig. 1. Fig. 6 is a detail perspective view.

15 is a rail having a switch-tongue 16.

17 is an iron box located on both sides of the rail 15 at a predetermined point, said box having removable covers 18.

19 are grooves formed on a portion of the box 17.

20 are rods or guides adapted to slide in the grooves 19. One end of these rods is cut away, as at 21, and one end of a switch-operating lever 22 is secured in said cut-away portion, as clearly shown in the detail perspective view, Fig. 6.

23 is a cam-block secured on the top of the switch-lever 22 over the rods or guides 20, said block having a lateral extension or flange 24. 25 is a similar block secured to the other end of the rods or guides. 26 is a flange similar to the flange 24. The flanges 24 and 26 work in the boxes 17, immediately under the cover 18.

27 is an iron box located as shown and provided with a cover 28.

29 is a lateral extension or lug inside the box, to which the lever 22 is pivoted by means of a bolt 30.

31 is a lateral extension integral with and outside of the box provided with suitable spike or bolt holes.

32 is the sleeper under rail 15, to which the box 27 is secured by means of spikes or bolts 33. The rail 15 rests on the lateral extension 31.

34 is another iron box having a cover similar to the other boxes. The end of the lever 22 works in this box.

35 is an opening or slot in one side of the box 34, through which a link or rod 36 is adapted to slide. One end of the rod or link 36 is connected, by means of a bolt 37, to the switch-tongue 16, while the other end is connected to the operating-lever 22 by means of a bolt 38. 39 is a slot in the rail 15, in which the bolt 37 slides when the switch is operated.

The operation is obvious and hence need not be described.

What we claim, and desire to secure by Letters Patent, is—

1. In a switch, a grooved base, guides adapted to engage said grooved base, a lever, one end of which is secured to said guides, the other to a switch-tongue, cam-blocks secured to said guides, said cam-blocks being located one on each side of a track-rail.

2. In a switch, a track-rail and switch-tongue, a box located on each side of the rail at a predetermined point a grooved base formed on a portion of said box, under the rail, guides adapted to work in said grooves, an operating-lever, one end of which is se-

cured to said guides, the other to the switch-tongue, cam-blocks secured to the guides, one on each side of the rail.

3. In a switch, a track-rail and switch-tongue, a lever one end of which is connected with said tongue, an iron box located on each side of the track-rail, cam-blocks secured to the free end of said lever, a lateral flange extending from the rear of each cam-block, said flange working in said iron box.

4. In a railway-switch, a track-rail and switch-tongue, a lever connected with said tongue, a box located at the fulcrum-point of said lever, a laterally-extending flange or lug inside of said box, to which the said lever is fulcrumed, and a laterally-extending flange outside of the box provided with spike or bolt openings whereby the box is secured to a block, said outside flange extending underneath the track-rail.

In testimony whereof we affix our signatures in presence of two witnesses.

HENRY M. HUME.
FREDERIC T. HUME.
